UNITED STATES PATENT OFFICE.

THOMAS C. SPELLING, OF NEW YORK, N. Y.

BOTTLE-STOPPER.

1,216,005.

Specification of Letters Patent.

Patented Feb. 13, 1917.

Application filed September 23, 1916. Serial No. 121,710.

To all whom it may concern:

Be it known that I, THOMAS C. SPELLING, a citizen of the United States, and resident of New York city, in the county of New York and State of New York, have invented certain new and useful Improvements in Bottle-Stoppers, of which the following is a specification.

This invention relates to combinations of bottles and bottle stoppers, and has for a purpose the provision of a device or mechanism to prevent fraud and imposition by substitution of an inferior or different liquid for that originally contained in a bottle; or similar container, said bottle or container to be made of any suitable substance.

It comprises, a bottle conventionally formed, for use with ordinary stopper, but having, in its neck and below its mouth, an interior trench, extending upwardly from the lowest point of the neck, terminating in a small oval opening, at one side, said trench and opening formed in the making of the bottle; a peculiarly formed stopper to be inserted in said side opening from the inside, and a puller inserted therein from the outside. According to one formation the extraction of the stopper through the side opening is contemplated, and, according to another, the extraction without breaking the bottle or without devoting to the task considerable labor and using special tools is impracticable.

The first mentioned formation will be described first. It contemplates the puller having the function, as inserted, of locking said ordinary stopper so that it cannot be extracted prior to the extraction of the side stopper without the bisection and destruction of the usefulness of the ordinary stopper. Nor can any other ordinary stopper be inserted prior to the extraction of the side stopper. The original contents of the bottle cannot be emptied from it until the side stopper is removed; and the function of the bottle is destroyed in such removal. Owing to its peculiar shape, no substitute can be provided for said side stopper in small quantity without a prohibitory expense, and the bottle cannot be again used without it, nor, in any event, without infringement of patent and proprietary rights, not to be contemplated as a possibility.

I have illustrated in the drawings the arrangement, in detail as well as in combination, the parts of the invention. I now pro-

ceed to a description of the same, aiding the description by the said drawings, forming parts thereof.

In the drawings, Figure 1 exhibits parts in place, except the stem and equipment of the puller which is embedded in the substance of the stoppers; Figs. 2, 3 and 4 are sectional views; Fig. 2 being a top view of a cross-section of the neck, showing the trench below the side extension made for the side stopper; Fig. 3 being a top view of a cross-section of the neck extending through said side extension, and Fig. 4 being a top view of a cross-section of said side extension showing therewithin a section of the side stopper and the hole made by the stem therein; Fig. 5 is a perspective view of the pull member exhibiting all its parts in place, and Fig. 6 is the same, showing the clip nearest the plate enlarged and the addition of other clips; Fig. 7 is a detached view of that part of the pull member hereinafter designated as the clip and designed, upon the application of force, to penetrate and mutilate the side stopper. Fig. 8 is a top view of the slot to be occupied by the neck of the clip in place. Fig. 9 is a perspective view of the side stopper. Fig. 10 is a sectional view of that form of the pull member shown in Fig. 5 the pull member in place showing the relation of all its parts to other parts of the device. Fig. 11 illustrates use of enlarged and added clips.

Referring more specifically to the drawings, wherein like reference characters designate corresponding parts in the several views, A represents the bottle, B a stopper which may be of any suitable substance but preferably of cork, slanted or straight, C a portion of the pull member formed to engage a suitable tool or machine to be used in extracting the side stopper, D a small oval plate, and E the side stopper, which like the ordinary stopper may be of any suitable substance, but preferably of cork.

The stem of the puller F is preferably of metal, large enough where the slot G appears to admit of the introduction of said metal clip, (Fig. 7), and is sufficiently reduced at H below the slot to facilitate the penetration of the substance of the two stoppers, having also the sharp point I, conducive to the same end. Said slot is a narrow incision in the stem, deep and wide enough to allow the insertion therein of the narrowed portion O, of the clip. The walls

thereof slant at an angle downwardly from side to side of the stem, making a sharp turn at J. The upper or inner wall is slightly beveled at K, on each side of the stem, in 5 order that the wings may bend in toward the stem, on the passage of the latter to place.

The clip is to be of sufficient strength not to yield in the process of extracting the 10 puller but sufficiently resilient for its ends to bend at L upwardly toward the stem of the puller as the latter moves inwardly in the act of insertion. It has the shoulders M and the interior shoulders N, the latter being 15 slotted from the central portion and depressed to act as props. The terminals of the clips are shaped as shown in Fig. 7, these being connected by the narrowed portion O, formed to occupy said slot, with frictional engagement, in bent or curved relation. The substance of the bottle will have 20 the free edges P at the side opening surrounding said oval opening interiorly. The small plate D is formed to fit into the oval space Q. The side stopper (Fig. 9) conforms in exterior shape and dimensions to 25 the interior surface of the space provided for it in the formation of the bottle, but is constructed slightly larger, in order that it may 30 expand when forced inwardly, and that the sealing substances may be impacted and firmly held in place. Its end R, designed to contact with the side of the ordinary stopper in use, is slightly concaved vertically and 35 is rounded at the upper and lower edges, as shown at S. The small plate (D) shown in the illustration is loosely adjusted around the neck of the stem.

In assembling, the point of the stem is 40 moved under pressure along the center of the side stopper and penetrates the ordinary stopper laterally to the point T, its movement being arrested by the arrival of the plate at the point of contact with the exterior surface of the side stopper. The position 45 of the several parts are then as follows: The lowest portions of the clip rest upon the exterior surface of the ordinary stopper at U and, although its portions not confined 50 within the slot are by the presence of the substance of the stopper through which it passes in, curved upwardly, its sharp points, having cut their ways in passing, now lie embedded in the substance of the stopper. 55 The edges of the plate now rest within the aforesaid edges of the bottle substance surrounding said oval space, though its position is changed in completion of the assembling as presently explained. The first act, 60 in assembling is to press the side stopper into the space provided for it, impacting it out of the way of the ordinary stopper. After the ordinary stopper has been inserted and all the parts of the puller have been placed 65 as above described, the plate is pressed down-

wardly until its upper surface is below said edges. The pressure upon and movement of the plate has two purposes and effects. One of them is to bring the upper surface of the plate below the surrounding edges of the 70 bottle substance; the other is the creation of an intenser contact of the substances of the two stoppers. Said plate, after above movement, is, by any suitable tool, or with the fingers, turned half around until its position 75 is as seen in Fig. 1, and its longer dimension extends across the shorter diameter of said oval opening, and portions of its upper surface are brought into contact with the under surface of said edge. By this act all the 80 parts of the device are brought into final place and firmly held. The portion of the puller represented by C rests in a plane outside the surface of the bottle, and, in addition to its principal office, aforesaid, it serves 85 as a shield to protect the bottle substance and prevent its breakage.

It is obvious that after the liquid is placed within the bottle the side stopper must be first inserted, then the ordinary stopper, then the puller. Then the plate is pressed 90 inwardly and is turned across the oval space, as before explained.

When the bottle is to be opened, the plate is first turned back to its original position 95 within the oval space; whereupon, force being applied to C, the first result of the outward movement is that the terminals of the clip, preceded by said sharp points, cut into the adjacent substance, until said shoulders 100 contact with the adjacent stem. The whole pull action results in a core or fragment of the said stopper, a large proportion of it, extending from end to end being torn from the central portion thereof and pulled 105 through said side opening, an important segment above a median line being detached and drawn through the aperture. The remnant of the side stopper and the ordinary 110 stopper may be then removed by any suitable 115 means and the contents of the bottle poured out.

Of course other means could be devised for closing the side opening, thus left without closure, and using the bottle for other than legal purposes but not without the act of so using it carrying the imprint of illegality. The side stopper, without which the contents of the bottle cannot be therein sealed, is entirely ruined with respect to 120 the uses for which it was designed; at any rate it cannot be used without the other parts of the device, or substitutes similarly constructed. But all the other parts of the device may be used again by the owner, 125 who may procure another side stopper, for use in connection with them.

It will be observed that the addition of another clip, shown in Fig. 11, illustrates a mere variation in construction, adding 130

merely a short neck at N, substituting the enlarged clip W and other X. Construction of the device according to the preceding description of the first formation contemplates use by the owner of the puller and bottle after the original contents have been emptied. But, in the case of the form illustrated in Fig. 11, the breakage of the bottle above the point of emplacement is practically necessary before its contents can be emptied. This can, however, if preferable, be accomplished without involving total destruction, because the bottle neck is weakened in preparation along the plane of the puller. The result of the enlargement of the clip (shown in Fig. 6) is that, when force is applied to the puller causing the terminals of the clips to spread apart, their divergence becomes so great that their passage through the neck of the side opening is obstructed. The same force causes a like spreading apart of the terminals of the other clips which in the act of inserting the puller have been embedded in the substance of the ordinary stopper. And owing to their increased length and spread, the force applied to the puller acts now along lines outside the circumference of the side opening, whereas, in the form of construction first described, said force acts along the lines Z, within said circumference. The obvious effect of the application of force, in both instances is to impact the substance of the stopper along these lines, and in the second formation to obstruct the movement of the clips.

If desired, or thought necessary, an additional side opening in the bottle may be formed and a pull member, fully equipped as above described, placed at right, or at an oblique angle across that above described and illustrated.

It will be understood that while I have herein illustrated the preferred embodiment of the invention, the latter is not restricted to the said special form of devices but is

capable of embodiment in such other forms and devices as will be within the scope of the hereto appended claims.

I claim:

1. A bottle closure comprising in combination a bottle neck having an end and a side opening, a stopper in each opening, and a retaining pin insertible through said side opening through the stopper therein and into the stopper in the end opening. 50

2. A bottle closure comprising in combination a bottle neck having an end opening and a side opening, a channel formed in the inner wall communicating with said side opening, a stopper in said side, and another in the end opening, and a retaining pin insertible in said side opening through the stopper therein into the stopper in the end opening. 60

3. A bottle closure comprising in combination a bottle neck, having an end opening and a side opening, stoppers in said side and end openings, a retaining pin comprising a pin insertible through said side opening, a clip carried by said pin flexibly supported to permit deflection of said clip upon withdrawal of said pin, and said clip mutilating said stopper in the side opening upon withdrawal of said retaining pin. 65 70

4. In a bottle closure, a bottle neck having a side opening of elliptical cross section, a stopper therein, a retaining pin insertible through said opening and stopper and a plate of elliptical outline insertible through the mouth of said opening and rotatable on said retaining pin to dispose its great diameter across the mean diameter of said opening. 75

Signed at New York, in the county of 85 New York and State of New York this 14th day of September, A. D. 1916.
